CIGARETTE AND CIGAR EXTINGUISHER

Albert J. N. Cecil, Washington, D. C.

Application April 23, 1956, Serial No. 580,009

6 Claims. (Cl. 131—256)

This invention relates to a novel extinguisher of extremely simple construction which may be efficiently employed for extinguishing the burning ends of cigars and cigarettes.

Considerable difficulty is encountered, especially by operators and passengers of motor vehicles, in completely extinguishing a cigar or cigarette before it is disposed of by being thrown from a vehicle or by depositing it in an ash tray. The throwing of lighted cigars and cigarettes from a vehicle is prohibited by law in some jurisdictions and attempting to completely extinguish a cigar or cigarette in an ash tray is quite difficult, and frequently the cigar or cigarette continues to smolder and often ignites other cigar and cigarette butts within an ash tray causing considerable annoyance, especially when this occurs when the windows of a vehicle are closed.

Accordingly, it is an aim of the present invention to provide an extinguisher of extremely simple construction which may be readily mounted in a motor vehicle and which may be effectively employed for extinguishing the burning ends of cigars and cigarettes by merely inserting such ends into an open top receptacle portion of the device.

A further object of the invention is to provide an extinguishing device which due to its unique construction will readily maintain extinguishing fluid therein even though the device is subjected to considerable vibration.

Various other objects and advantages of the invention will hereinafter become more fully apparent from the following description of the drawing, illustrating a presently preferred embodiment thereof, and wherein:

Figure 1 is a top plan view of the extinguisher shown in an applied position;

Figure 2 is a longitudinal sectional view thereof, taken substantially along a plane as indicated by the line 2—2 of Figure 1, and

Figures 3 and 4 are enlarged cross sectional views of the extinguisher, taken substantially along the lines 3—3 and 4—4, respectively, of Figure 2.

The extinguishing device in its entirety is designated generally 6 and includes a resilient support, designated generally 7, a tank 8 and an upwardly opening receptacle 9.

The resilient support 7 includes an end portion 10 which is adapted to be attached to a surface of a substantially vertical supporting member 11, such as a portion of a vehicle instrument panel. Said end portion 10 is illustrated as a suction cup which is attached in a conventional manner to the panel 11. However, other forms of attaching members could be substituted for the suction cup 10. The other end of the resilient support 7 is defined by an elongated socket member 12 which opens in a direction away from said end portion 10. The resilient support also includes a resilient intermediate portion 13 extending between and connecting the end portions 10 and 12.

The resilient intermediate portion 13, as illustrated in Figure 2, preferably constitutes an elongated hollow neck

2

14 which may be formed of rubber or other flexible material and which may constitute an integral projection of the central portion of the outer side of the suction cup 10. The neck 14 extends through a central opening 15 in the inner end wall 16 of the socket 12 and has an end wall 17 which may be molded or otherwise secured to the extremity thereof and which is disposed within the socket 12 and is larger than the neck 14 for engaging the inner side of the end wall 16 around the opening 15. The end wall 17 may be secured to the neck 14 by being molded thereto and to the inner side of the wall 16, after the neck 14 is inserted through the opening 15. The neck 14 is also provided with an external rib 18 which is spaced slightly from the end wall 17 and which engages the outer side of the end wall 16 around the opening 15, to cooperate with said end wall 17 for connecting the socket 12 immovably to the neck 14. A coil spring 19 is disposed in the hollow interior of the neck 14, preferably between end plates or discs 20 which line the ends of the hollow interior of the neck 14 to prevent the ends of the springs from becoming embedded in the ends of the neck. The spring 19 is maintained by the disks 20 under slight compression and aids in resisting flexing of the neck 14.

25 The tank 8 is of substantial length relative to its cross sectional size and the cross sectional shape thereof corresponds to the cross sectional shape of the socket 12 and is of sufficiently smaller size so that an end portion of the tank 8, located adjacent its open end 21, can be slidably inserted into the socket 12 through the outer open end 22 thereof. The socket 12 and tank 8 are illustrated as being of circular cross section but could be of any other desired corresponding cross sectional shape. A plug or stopper 23 fits detachably into and provides a 30 liquid-tight seal for the tank end 21 and may be formed of any suitable material, such as rubber or cork. An outer peripheral portion of the stopper 23 and/or the wall of the tank 8 frictionally engages the socket 12 to retain the tank in engagement with said socket or to 35 permit the tank to be forcibly pulled out of engagement with the socket. When the aforementioned tank end is fully inserted into the socket 12 so that the stopper 23 abuts the end wall 17 and the receptacle 9 is in an upright position, a vent opening 24 of the tank 8 will register with a communicating vent opening 25 of the socket 12.

40

The open top receptacle 9 is preferably cup shaped and formed integral with the top portion of the other outer end 26 of the tank 8. The receptacle 9 comprises a bottom 27 which may be either flat or slightly dished, and an upstanding surrounding wall 28. At least the central portion of the bottom 27 constitutes a part of the top portion of the tank 8 and is provided with at least one opening or aperture 29 forming a communicating passage between the interior of the tank 8 and the interior of the receptacle or cup 9.

The tank 8 is adapted to be filled with water 30 or other suitable fire extinguishing liquid, nearly to the capacity thereof, as illustrated in Figure 2. The tank 8 is normally maintained by the resilient support 7 with its longitudinal axis substantially horizontal, as seen in Figure 2, so that the liquid level will be disposed slightly below the topmost portion of the tank 8 into which the apertures 24 and 29 open. Thus, no water will normally be contained in the receptacle 9. When it is desired to extinguish a cigar or cigarette, not shown, the burning end thereof is inserted into the receptacle or cup 9 through its open top and pressure is exerted thereby against the bottom 27 to cause the resilient intermediate or neck portion 13 to yield or flex downwardly. A slight flexing of the portion 13 is sufficient to cause the tank 8 to be inclined downwardly and outwardly toward its outer

end 26, so that a portion of the liquid 30 will flow through the passage 29 into the cup 9 for extinguishing the burning end of the cigar or cigarette. As this occurs, air will enter the tank 8 through the apertures 25 and 24. When the cigar or cigarette is removed from the cup 9 and a downward pressure thereon no longer exists, the intermediate portion 13 will be spring biased back to its normal horizontal position for returning the tank 8 to a horizontal position as shown in Figure 2, and so that the liquid will drain from the cup 9 through the passage 29 back into the tank 8 and at the same time air will escape through the apertures 24 and 25. The portion 13 is of sufficient strength to maintain the tank 8 when filled with liquid substantially horizontal. It will be obvious that the extinguished cigarette or cigar may be disposed of in an ash tray or otherwise after it has been extinguished, as previously described.

The resilient portion 13 in addition to yieldably supporting the tank 8 and receptacle 9 for the purpose heretofore described, additionally provides a cushioning means between the supporting element 11 and tank 8 for absorbing vibrations of the part 11 to prevent such vibrations being transmitted to the tank 8 and which might cause the liquid 30 to be splashed therefrom outwardly through the passage 29 or the vent apertures 24 and 25. The resilient portion 13 will also prevent the extinguisher 6 from being knocked out of engagement with the supporting element 11 in the event that it should be accidentally struck.

The tank 8 can be slidably withdrawn from the socket 12 and the plug 23 removed for refilling the tank when necessary. During refilling, the tank end 21 is held in an uppermost position and a finger is placed over the passage 29 to prevent the liquid from escaping therethrough. This can be readily accomplished, where the extinguisher 6 is used in an automobile, at a gasoline station while the vehicle is being refueled. It will also be apparent that the tank 8 and receptacle 9 may be readily cleansed to remove any collected accumulation of ashes.

The tank 8 may also be refilled through the passage 29.

Various other modifications and changes are contemplated and may obviously be resorted to, without departing from the spirit or scope of the invention as herein-after defined by the appended claims.

I claim as my invention:

1. In an extinguishing device of the character described comprising an end portion constituting an attaching member adapted to be connected to a substantially upright supporting member, an elongated tank adapted to contain a fire extinguishing liquid including an inner end and an outer end, connecting means forming a connection between said attaching member and the inner end of said tank for supporting the tank with its axis substantially horizontal, an open top receptacle mounted on the outer end of said tank, said receptacle having a passage communicating with the interior of the tank and opening into the bottom of the receptacle, and said connecting means including a resilient portion whereby the tank may be swung downwardly by a downward pressure exerted on the receptacle for causing a part of the liquid therein to pass through said passage into the receptacle and for causing the liquid to return to the tank from the receptacle when the tank is returned to a horizontal position by the resiliency of said part of the connecting means.
2. In an extinguishing device as in claim 1, said tank having an upwardly opening vent port adjacent the inner end thereof.
3. In an extinguishing device as in claim 1, said attaching member comprising a suction cup.
4. In an extinguishing device as in claim 1, said connecting means including an elongated socket having a cross sectional size and shape adapted to slidably receive said inner end of the tank.
5. In an extinguishing device as in claim 4, said resilient part comprising a neck extending between said attaching member and the adjacent inner end of said socket, said neck being formed of flexible material and defining an elongated chamber, and a spring contained in said neck chamber and cooperating with the neck for normally supporting the tank with its axis in a horizontal plane and permitting the tank and socket to be rocked relative to the attaching member.
6. In an extinguishing device as in claim 5, said inner end of the tank constituting the filling end thereof, and a removable stopper for closing and sealing said inner tank end.
